(57) **CLAIM**

The ornamental design for a paint spray gun tip, as shown and described.

DESCRIPTION

FIG. 1 is a perspective view of the paint spray gun tip, in accordance with a first embodiment.

FIG. 2 is a front view of the paint spray gun tip, in accordance with the first embodiment.

FIG. 3 is a back view of the paint spray gun tip, in accordance with the first embodiment.

FIG. 4 is a right side view of the paint spray gun tip, in accordance with the first embodiment.

FIG. 5 is a left side view of the paint spray gun tip, in accordance with the first embodiment.

FIG. 6 is a top view of the paint spray gun tip, in accordance with the first embodiment; and,

FIG. 7 is a bottom view of the paint spray gun tip, in accordance with the first embodiment.

The broken lines in the drawing illustrate portions of the paint spray gun tip which form no part of the claimed design.
